ELECTRICAL RESISTANCE UNIT.

Application filed February 4, 1925. Serial No. 6,732.

The invention relates to improvements in electrical resistance units. More particularly it relates to rheostats of the compression type, which may be for example of the order of 5 one or more megohms, or may be of very much less resistance even down to a few ohms only. The invention has been particularly developed for the resistances of high order first mentioned. It may therefore conveniently 10 be described and illustrated as it may be applied for use as a grid leak used in connection with a thermionic tube or the like in radio receiving apparatus. It may, however, be put to other uses; and when constructed 15 in a different order of values of resistance, suitable for the purpose, it may be applied as a means for controlling volume in audio frequency amplifiers, or in the primary or in the secondary of a transformer or in any of a 20 wide variety of other situations.

It is a particular object of the invention to provide a grid leak which is adjustable through a wide range; and to provide a construction wherein the adjustment is easily 25 made, the materials and their processes of manufacture simple and inexpensive, and the accuracy of the resulting product satisfactory. It is an especial feature to make a 30 grid leak in which the parts can be made largely by automatic machinery and assembled with accuracy without skill and with little labor.

To this end the invention provides a cup, being preferably a cylindrical shell closed 35 at one end, and there constituting one terminal, within which cup is a hollow cylindrical resistance pad through the thickness of which the electrical circuit passes to the shell from a cylindrical, expandible compressor within. 40 The latter is conveniently formed by cutting slots along a tube of resilient metal, deeply from one end thereof, thus converting its walls into spring sectors, and providing at the mouth of this element a cam for spreading 45 these sectors radially. The cam may be a loose steel ball operated by a screw extending in the axial direction for forcing it into the mouth of said element, as far as desired, thus expanding the sectors radially against the 50 said resistance medium, which latter is of such a nature that its resistance decreases as its compression increases. A composite cap, closing the entrance to the cup, provides this screw element and an exterior terminal insulated from the shell body of the cup. Pref- 55

erably, it is so arranged that an insulating bushing screws into the shell and supports interiorly a metallic part having an axial screw with interior plunger head to press the ball, and with exterior operating head 60 or handle. A loose inside piece may intervene between the screw and the ball, to transmit thrust of the screw to the ball. This thrust, converted to radial pressure by its cam expansion of the compressor, compresses 65 the cylindrical resistance sheet against the cylindrical interior of the shell. By the construction described the compression may be very considerable, and will be approximately uniform. The current passes from the cap 70 terminal through the screw, plunger, transmitter, compressor, resistance and shell to the shell terminal.

The construction thus described is extremely simple mechanically requiring but 75 few operations of manufacture, and these can be performed by automatic machinery; while its results have been found very satisfactory electrically. The resistance pad may be made of absorbent material such as cotton cloth, 80 or blotting paper, in and among the fibres of which are finely divided deposits of conducting material, as carbon or metallic silver. For example, blotting paper may be soaked in a carbon suspension ink, and dried; 85 or in silver ammonium nitrate and then dipped in formaldehyde to precipitate metallic silver. When cleaned and dried, and insulated in the apparatus described, a resistance results which can be adjusted by screw 90 pressure, with satisfactory accuracy through a wide range; as, for example, in the particular apparatus herein more specifically described, a range of from one-half megohm to fifteen megohms has been found easily at- 95 tainable.

The invention may be applied in various ways, one of which is illustrated in the accompanying drawings and description. It is intended that the patent shall cover, by suitable expression in the appended claims, whatever features of patentable novelty exist in the invention disclosed.

In the drawings:

Figure 1 is a side elevation of a preferred 105 form of grid leak;

Figure 2 is a medial longitudinal section of the same;

Figure 3 is a transverse section through the apparatus on line 3—3 of Figure 2; 110

Figure 4 is an elevation showing the grid leak mounted between conductor terminals, on a base of ordinary type; and

5 Figure 5 is an enlarged side elevation of a detail of Figure 2.

Referring to the drawings, a metal shell or cup 1 is represented, conveniently made on a screw machine from a brass rod by drilling a chamber 11. The exterior is smooth and 10 adapted to be mounted on an ordinary base 4, having an exterior screw 14 and washer 13 for clamping one clip 12 of such a base. Thus this shell 1 becomes one terminal of the 15 grid leak. The mouth of the shell or cup is filled by a cap or plug, one part of which 2 is of brass and constitutes the other terminal, while another part 20 is of rubber, a phenolic condensation product, or the like insulator and supports this terminal 2 in the mouth of 20 the cup, together with an axial screw 25 with external insulating handle 25'. In Figure 4 the part 2 is seen held by the other clip 24, of the base 4. The inner end of screw 25 reaches into an axial cavity 26 which is open 25 into the interior of the cup. This cavity 26 houses the stem of a loose sliding plunger or follower 27 whose somewhat larger head is hollowed to adapt it for engaging a small steel ball 30 within the cup 1. The insulating portion 20 of the cap is preferably an annular bushing fast on the metal part 2 of the cap, having an external screw thread for engaging the screw thread in the mouth of the cup 1 and reinforced by an internal steel 30 collar 31 upon the edge of which the end of the tubular exterior 2' of the part 2 is turned over. Thus there is provided a closed cylindrical chamber 11, with its body 1 constituting one terminal and its closure 2 constituting 35 the other, and there is an axial screw 25 in the latter, adjustable from without, for thrusting the ball 30 more deeply into the chamber, or for letting it recede, and for connecting it electrically with the terminal 2.

40 Within the chamber is an insulating disc 15 at the bottom of the chamber; a high resistance hollow cylindrical pad 16; and a metallic annular compressor 17 adapted to compress the pad against the shell walls whenever it is expanded by the thrusting of ball 30 into its mouth. The compressor is conveniently made with four separated sectors 17^a by slitting a tube or solid rod of spring brass by saw cuts 17^b deeply from one end, throughout the greater part of its length. But at its other end a portion of metal 17^c is left for holding the sectors all together. The free ends 17^d of the sectors being set so as to have a slight circumferential marginal clearance, 45 and being centrally countersunk, as seen in Figures 2 and 5, so as to present a conical bearing surface against which the ball 30 engages when it is thrust inward by the screw 25. In this respect the ball acts as a cam on the beveled ends 17^d of the sectors. The sec-

tors are thus arranged somewhat as lagging round the interior of the pad 16 and are capable of being expanded to apply pressure radially outward on this cylindrical pad. The ball is automatically centered both by these 70 ends of the sectors and by its own follower 27, which has a cup shaped head. Thus the pressure of the sector arms 17^a is applied in approximately uniform manner radially outward, upon the sheet or pad of resistance material 16 compressing it against the cylindrical wall of the cup 1 with a pressure which may be relatively great considering the smallness and simplicity of the parts by which it is generated, and which will remain permanently at whatever degree it may be set. Upon retraction of the screw 25, the elasticity 75 of the compressor arms 17^a will spring them back again toward the axis, so far as the retraction of ball 30 permits, thus relieving 80 pressure on the pad 16 to a corresponding extent.

The pad 16 may be made from very simple materials as for example from blotting paper which may be dipped in a fluid carrying finely divided carbon in suspension as for example in ordinary black drawing ink. After being thoroughly soaked for two or three minutes and then dried a suitably sized section of a sheet of this may be rolled into tubular form and used for the resistance pad 16. With increase of compression the carbon particles are forced closer together thus decreasing the electrical resistance of the sheets to currents passing through its thickness. Another method of preparing the resistance pad is to impregnate a pad of fibrous material such as cotton or wood pulp blotting paper with a liquid from which subsequently a metallic precipitate is formed in finely divided 95 condition distributed through the mass of the pad. An example of this is to impregnate the pad with silver ammonium nitrate. A saturated sheet is then dipped into a solution of formaldehyde which precipitates pure metallic silver in minute distributed particles throughout the body of the bed. Other products of the reaction having then been washed out in water the pad is to be dried and then is ready for use. The details of this process 100 may be carried out like the method now commonly used for putting silver upon glass in order to make a mirror, beginning with the soaking of the paper in stannous chloride and then to wash it out thoroughly, afterward applying the silver ammonium nitrate. 115

120 By using a sheet of high resistance compressive material and passing the current through its thickness the sheet thus acting as a very short conductor having large cross sections, viz: approximately the area of the sheet, it is possible to use for the resistance a material which has very high resistance, and yet by suitable design and adjustment to control the results with considerable accuracy. 130

When using the invention for resistances of lower order suitable modifications will naturally be made. When only a fixed resistance of specified value is wanted, such can be made by the described invention, and after being adjusted to the proper value the knob 25' can be cut off, leaving it practically impossible to change the adjustment.

I claim:

10. 1. A resistance unit comprising a cylindrical sheet of resistance material whose radial thickness constitutes the lengthwise dimension of the resistance, and compression means acting radially thereon.
15. 2. A resistance unit comprising a shell; a sheet of resistance material whose radial thickness constitutes the lengthwise dimension of the resistance, lining its interior; and means compressing the sheet radially against 20 the shell.
25. 3. A resistance unit comprising a shell; a sheet of resistance material whose radial thickness constitutes the lengthwise dimension of the resistance, lining its interior; an expandible compressor within; and manually operative means for expanding the compressor against the resistance material and shell.
30. 4. A resistance unit comprising a cylindrical shell; a cylindrical sheet of resistance material within it; lagging within said cylindrical sheet; a circular cam; and means acting through the cam to thrust the lagging radially outward thereby compressing said sheet against said shell.
35. 5. A resistance unit comprising a cylindrical shell; a cylindrical sheet of resistance material within it; lagging within said cylindrical sheet; a circular cam; and means acting through the cam to thrust the lagging 40 radially outward thereby compressing said sheet against said shell; and connections for making the circuit through the cam and lagging.
45. 6. A resistance unit comprising a cup and a plug closure therefor; these two constituting electric terminals and being insulated from each other; a sheet of resistance material within and lying around the side of the shell; and screw operative means for connecting the resistance electrically and compressing it mechanically between the plug and the cup.
55. 7. A resistance unit comprising a cylindrical shell of conducting material, a plug closing one end of it having a terminal insulated from it; and an interior connection from said terminal to the side of the shell through a compressive resistance.
60. 8. A resistance unit comprising a cylindrical shell of conducting material, a plug closing one end of it having a terminal insulated

from it; an interior connection from said terminal to the shell through a compressive resistance, comprising a screw and expanding element cooperating therewith and a resistance element lining the side of the shell and arranged to be pressed by the expansion of the said expanding element. 65

9. A resistance unit comprising a shell and resistance sheet lining its interior; spring 70 lagging within the sheet; a ball cam bearing against the ends of the spring lagging; and a screw adapted to push the ball axially and thereby to expand the lagging radially, compressing the sheet. 75

10. A resistance unit comprising a cup and ball in the mouth of the cup, means to force the ball inward; and resistance means within the cup arranged to be compressed; and transmitting means applying pressure thereto by the movement of the ball. 80

11. A resistance unit comprising two terminals mechanically engaged together one of which has a circular portion and an annular resistance within the circular portion combined with means arranged to be operated by axial thrust and to act with radial thrust for compressing the resistance against the circular terminals. 85

12. A resistance unit comprising in combination two terminals; a resistance of compressive material; a moving part on one of the terminals adapted by cone and a cam connection, wherein the cone and cam are engaged together to produce a spreading motion, to apply pressure to the resistance material, to vary its resistance; the said resistance material and the main course of flow through it being positioned laterally of the said cone. 90

13. A resistance unit comprising in combination terminal elements one of which is tubular and a tubular pad having finely divided conducting material disseminated through it so that the whole is of high resistance, variable by varying the degree of compressing of the pad, within said tubular terminal; and means to compress said tubular pad and tubular element together radially in tubular contact. 100

14. A grid leak comprising in combination terminal elements and a pad having finely divided conducting material disseminated through it, of which the resistance is variable by varying the degree of compressing of the pad; in which the compressive material is a mat consisting mainly of wood pulp in the nature of blotting paper. 115
